UNITED STATES PATENT OFFICE.

BERTRAM HANSEN AND PETER J. RAMION, OF SYRACUSE, NEW YORK.

HAM-CURING DEVICE.

Application filed January 3, 1928. Serial No. 244,192.

This invention relates to a ham curing device by which brine or other pickling fluid may be injected into the ham or other meat near the bone or bones for curing and preserving the same.

The main object is to provide a simple and efficient device of this character capable of being inserted by pressure into the meat for discharging the curing liquid near the bones thereof without liability of admitting air through the incision made by the instrument, it being understood that the deterioration of the meat usually begins near the bone or at some other part of the meat which may be exposed to air.

Other objects and uses relating to specific parts of the device will be brought out in the following description.

In the drawings:—
20 Figure 1 is a side elevation, partly broken away, of a ham curing device embodying the various features of the invention.

Figure 2 is a longitudinal sectional view, partly broken away, of the same device, the 25 valve and outlet for controlling the flow of liquid through the device being closed.

Figure 3 is a sectional view, partly broken away of a part of the same device, showing the valve and outlet in their open positions.

30 Figure 4 is a transverse sectional view taken in the plane of line 4—4, Figure 1.

As illustrated, this device comprises a valve case —1— having a transverse opening —2— therethrough to form a valve chamber 35 and also provided with a lengthwise inlet opening —3— and a lengthwise guide opening —4— extending longitudinally from opposite sides of the transverse opening or valve chamber —2—.

40 A plunger valve —5— is reciprocally movable in the valve chamber —2— across and between the lengthwise openings —3— and —4— and is provided with a transverse opening —6— movable into and out of registration with the lengthwise openings —3— and —4—, but is yieldingly held out of registration with said lengthwise opening by coiled spring —7— as shown in Figure 2.

The lower end of the valve chamber —2— 50 is closed by a removable cap —8— screwed or otherwise secured to the adjacent end of the valve chamber and forming a seat for the lower end of the spring —7— having its upper end engaged with the lower end of 55 the plunger valve —5—.

The valve chamber —2— is preferably

cylindrical while the valve —4— is of the same cross sectional form and size to closely fit the walls of said chamber to form a liquid-tight joint therewith when the valve 60 is closed.

The side of the valve facing the guide opening —4— is provided with a cam face —9— just below the opening —6— or between said opening and the lower end of 65 the valve, the portion of the valve just below the cam —9— being recessed to receive the adjacent end of a delivery tube —10— which is movable endwise in a tubular guide —11— and is provided at its outer or front 70 end with a forwardly tapered needle —12—.

The front end of the guide opening —4— is closed by a tubular plug —13— screwed or otherwise secured in the adjacent end of the valve case —1— to form a liquid-tight 75 joint therewith and also to form a part of the guide for the axially movable delivery tube —10—.

The inner end of the delivery tube —10— adjacent the valve —5— is slightly enlarged 80 to form a shoulder which is adapted to be engaged by the adjacent end of a coiled spring —14— having its other end engaged with the inner end face of the tubular bushing by yieldingly holding the inner end of 85 the delivery tube —10— against the adjacent portion of the valve —5—.

The rear or inner end of the guide tube —11— is screwed or otherwise secured in the front end of the bushing —13— to hold 90 it against axial or angular movement. The guide tube —11— is cylindrical and of relatively small but uniform diameter from end to end or from the front end of the bushing —13— to the rear end of the needle —12— 95 to permit it to readily enter any meat portion of the ham to the bone thereof.

The delivery tube —10— is also cylindrical and of substantially the same diameter as the inner diameter of the guide tube 100 —11— so as to closely fit the walls thereof throughout the length of the guide tube to form a liquid and air-tight joint therewith.

A handle —15— is secured to the rear end of the valve case —1— around the inlet opening —3— and is provided with a central lengthwise opening —16— registering with said inlet opening to permit the flow of liquid through the device when the valve —5— is opened.

110 A tubular nipple —17— is secured in the rear end of the handle —15— in alinement

with the lengthwise opening —16— and is connected by a union —18— to an extension nipple —19— which, in turn, may be connected by a flexible or other pipe, not shown, 5 to the source of supply for the brine or other curing liquid.

A valve operating lever —20— is extended across and against the outer or upper end of the valve —5— and has its front end offset downwardly and pivoted at —21— to a boss —22— on the valve case —1— at the rear of the valve chamber —2—.

The front end of the lever extends lengthwise of and directly over the handle —15— in sufficiently spaced relation thereto to permit it to be operated for opening the valve —5— against the action of the spring —7— which normally tends to urge the valve —5— and free end of the lever —20— outwardly to 20 the position indicated in Figures 1 and 2.

Suitable means is provided for limiting the outward movement of the valve and free end of the lever consisting, in this instance, in providing the downwardly offset portion 25 of the front end of the lever with a shoulder —23— extending forwardly some distance beyond the vertical plane of the pivot —21— and adapted to engage the upper face of the adjacent portion of the valve case as shown 30 more clearly in Figure 1.

The opening —6— extends diametrically through the valve —5— at right angles to the axis thereof and is movable into and out of registration with the inlet and outlet 35 ports —3— and —4— and in order to maintain proper alinement of the passage —6— with the ports —3— and —4— when the valve is opened the upper end of the valve is reduced and flattened at —24— to rest in a 40 similarly formed recess —25— in the underside of the adjacent portion of the lever —20—.

This connection between the lever —20— and outer end of the valve —5— is particularly simple and efficient in holding the valve 45 against turning movement but obviously many other forms of connections may be used without departing from the spirit of this invention.

The delivery tube —10— is provided near its distal end with a radial discharge opening or openings —26— which are movable within and beyond the adjacent end of the guide tube —11— as the delivery tube is 50 reciprocated axially.

The needle point or entrant member —12— is screwed or otherwise secured to the distal end of the delivery tube —10— close to but slightly in front of the openings —26—, the rear end of said entrant member —12— being of substantially the same external diameter as that of the guide tube —11— so as to abut against the adjacent end of the 55 guide tube when the delivery tube is turned to its innermost position by the

spring —14— at which time the discharge openings —26— will be closed by the adjacent end of the delivery tube.

That is, when the pressure upon the lever —20— is released and the valve —5— is allowed to open by the action of the spring —7— the delivery tube will be moved rearwardly by its spring —14— to cause its rear end to enter the recess —9— below the cam surface —9— while the discharge openings —26— in the distal end of the delivery tube will be moved inwardly within the adjacent end of the guide tube —11— at which time the passage of the liquid from the inlet port —3— to the outlet port —4— and delivery tube —10— will be cut off by the valve —5— and the discharge openings —26— will be closed by the surrounding portion of the guide tube —11—.

The entrant member —12— is imperforate 85 and forms a closure for the distal end of the delivery tube just in front of the openings —26— so that when the valve —5— and delivery tube are in their normal positions of rest the rear end of the entrant —12— will 90 effectively close against the adjacent end of the guide tube and, together with the closing of the discharge opening —26— by said guide tube, forms a seal to prevent the entrance of air through the delivery tube and 95 into the meat when the distal end of the device is inserted into said meat.

Operation.

Assuming that the movable parts of the 100 device are in their normal positions of rest and that it is desired to inject a curing fluid into a ham or other meat and that the nipple —19— is suitably coupled to a source of supply for the curing liquid either by gravity 105 or other pressure, this liquid will then flow through the passage —16— of the handle —15— and thence into the inlet port —3— of the valve case —1—. The device may then be supported by hand by means of the 110 handle —15— and the lever —20— be pressed by the same hand for an instant for operating the valve —5— to register its passage —6— with the ports —3— and —4— and at about the same to cause the cam —9— 115 to engage and move the delivery tube —10— forwardly for temporarily opening the discharge openings —26— beyond the adjacent end of the guide tube —11— so as to fill the delivery tube and thereby to expel 120 the air therefrom about which the lever —20— may be released to allow the valve —5— to close and also to permit the return of the delivery tube —10— to its closed position.

The device is then urged forwardly to cause the needle point —12— and guide tube —11— to enter the meat to the required depth or until the needle point —12— is in proximity to the required depth or until the 125

needle point —12— is in proximity to the bone of the meat at which time the lever —20— will be again operated to depress the valve —5— against the action of its retracting spring —7— until the passage —6— registers with the inlet and outlet ports —3— and —4— during which time the cam —9— will have engaged and moved the delivery tube —10— forwardly a sufficient distance to expose the discharge openings —26— at the rear end of the guide tube thus permitting the discharge of the curing liquid at the required depth within the meat.

When the required amount of brine or other curing liquid has been injected into the meat in the manner just described the hand pressure upon the lever —20— is released to allow the spring —7— to return the valve —5— to its closed position while the spring —14— serves to return the delivery tube —10— to its closed position, it being understood that sufficient clearance is left between the rear end of the delivery tube and bottom wall of the recess —9'— to allow the rear end of the needle point —12— to engage the adjacent end of the guide tube to form a liquid and air tight joint therewith and thereby to retain a sufficient quantity of the curing fluid within the delivery tube to hermetically seal the same against the entrance of air.

It will be observed that the various parts of the device are smooth and easily cleansed. If it should be desired to remove the valve —5— for cleansing the same or the interior of the valve chamber —2— the screw cap —8— may be easily removed and the delivery tube —10— withdrawn forwardly against the action of the spring sufficiently to allow the valve —5— and its spring —7— to be withdrawn from the lower end of the valve chamber. On the other hand, if it is desired to cleanse the delivery tube the bushing —13— may be unscrewed from the valve case to permit the same with the guide tube —11— thereon and the delivery tube to be withdrawn forwardly from the valve case whereupon the needle point —12— may be unscrewed from the forward end of the delivery tube to permit the latter to be cleansed internally as well as externally.

Again, if the delivery tube or any of the passages leading thereto should become clogged from any cause the coupling member —17— at the proximal end of the handle —15— and the needle point —12— may be removed from their respective parts whereupon the valve —5— may be depressed by the handle —20— to bring its passage —6— into alinement with the ports —3— and —4— whereupon a wire or equivalent cleaning device may be passed through the registering passages to expel any matter which may have lodged therein.

65 What we claim is:—

1. In a meat curing device, a valve case having a valve chamber and ports leading from opposite sides of said chamber, a valve reciprocally movable in said chamber and provided with a passage therethrough movable into and out of registration with said ports, means for conducting a curing fluid to one of the ports, a guide tube having one end secured to the valve case around the other port, a delivery tube reciprocally movable in the other port and extending through and beyond the outer end of the guide tube and provided with a discharge opening normally closed by said guide tube, and means actuated by the opening movement of the valve for moving the delivery tube axially sufficient to expose its discharge opening beyond the adjacent end of the guide tube for discharging the fluid therethrough. 70 75 80

2. In a meat curing device, a valve case having a valve chamber and ports leading from opposite sides of said chamber, a valve reciprocally movable in said chamber and provided with a passage therethrough movable into and out of registration with said ports, means for conducting a curing fluid to one of the ports, a guide tube having one end secured to the valve case around the other port, a delivery tube reciprocally movable in the other port and extending through and beyond the outer end of the guide tube and provided with a discharge opening normally closed by said guide tube, and means actuated by the opening movement of the valve for moving the delivery tube axially sufficient to expose its discharge opening beyond the adjacent end of the guide tube for discharging the fluid therethrough. 90 95 100

3. In a meat curing device, a guide tube, a delivery tube reciprocally movable axially and provided with an inlet in one end and a tapered entrant member on its other end, said delivery tube having an outlet adjacent the entrant member and normally closed by the guide tube, means operable at will for moving the delivery tube endwise to expose the outlet beyond the adjacent end of the guide tube, and means for conducting a curing fluid into the delivery tube. 105 110 115

4. In a meat curing device, a valve case having a valve chamber and ports leading to and from said chamber, a self-closing valve controlling said ports, means for supplying a curing fluid to one of the ports, a delivery tube connected to the other port and provided with a discharge opening, means normally closing said discharge opening, means operable at will for opening said valve, and means actuated by the opening movement of the valve for causing a relative movement of the delivery tube and its outlet closing means for opening said outlet. 120 125

5. In a meat curing device, a valve case 130

having a valve chamber and co-axial ports leading to and from said chamber at right angles thereto, a plunger valve movable in said chamber and provided with a transverse passage movable into and out of registration with said ports as the plunger is reciprocated, yielding means normally holding the valve in its closed position, means operable at will for opening the valve, a handle secured to one side of the valve case and provided with a passage alined with said ports, a guide tube secured to the other side of the valve case in alinement with said ports, a delivery tube reciprocally movable endwise of and within the guide tube and having its 15 distal end provided with a tapered entrant member and an outlet opening normally closed by said guide tube, yielding means for holding the guide tube in its normal position, and means actuated by the opening 20 movement of the valve for shifting the delivery tube from its normal position to open the outlet.

In witness whereof we have hereunto set our hands this 20th day of December, 1927.

BERTRAM HANSEN:
PETER J. RAMION.
